United States Patent Office.

GEORGE H. MILLER; OF LEAVENWORTH, KANSAS.

Letters Patent No. 102,956, dated May 10, 1870.

HOT-AIR FURNACE.

The Schedule referred to in these Letters Patent and making part of the same.

To all whom it may concern:

Be it known that I, GEORGE H. MILLER, of Leavenworth, in the county of Leavenworth and State of Kansas, have invented a new and valuable Improvement in Furnaces; and I do hereby declare that the following is a full, clear, and exact description of the construction and operation of the same, reference being had to the annexed drawings making a part of this specification, and to the letters and figures of reference marked thereon.

Figure 1 of the drawings is a representation of a central vertical longitudinal section of my invention.

Figure 2 is a transverse vertical section of the same.

Figure 3 is a detailed view, showing the method of attaching the pipes to the wall of the radiator.

My invention relates to means for heating houses, and consists in certain improvements in the construction and arrangement of the fire-pot, grate, flues, hot-air drum, and cleaning-pipes, designed to form a satisfactory and efficient furnace, easily kept in order, and capable of heating and transmitting large quantities of air.

The letter A of the drawings designates the brick foundation, within which is the ash-pit.

B represents the wall of brick, forming the hot-air chamber, around the furnace.

C represents the furnace proper, consisting of an external corrugated tapering shell, D, its semi-cylindrical corrugated cap E, the feeding-tube F, and the lining-plate or fire-pot G.

The shell D is arranged with an upward flare, for the purposes of better draught and greater fire-surface. It is corrugated, to increase its heating surface, and is provided with a flanch, d, around its upper edge, having a continuous channel, a, in its upper surface, to correspond to a bead or ridge, e, formed on the under side of the flanch e of the corrugated cap e.

The lining-plate G has a tapering form similar to the shell D. It is arranged within the shell in such a manner that an air-chamber, H, is formed between the two.

Air is conducted into this chamber by means of the flues z z.

Perforations n n are made around the top of the lining-plate, to permit the air to pass into the fire-pot, and secure the combustion of the gases.

This flue or air-chamber H acts, also, as a preservative of the lining-plate.

The feeding-tube F is cast separately from the case or shell of the furnace, and is bolted to the cap E. The object attained by this arrangement is important, and consists in obviating the liability of the feeder to crack. When it is cast in the same piece with the

shell, it will be often at a red heat at its inner end, while the door of the flue may be cool.

Through the door of the feeder a perforation, f, is made, to permit the entrance of air.

K represents the grate, composed of the fish-bellied bars k k, provided with the pendent arms l l, pivoted at their lower ends to the connecting-bar g, to the end of which is attached the shaker m.

The grate-bars k k are slotted centrally, at i, in such a manner as to form double bars, connected at the ends, which are formed into journals, to allow of the free movement of the bars in the journal-seats, when operated by the shaker m.

Great power is obtained by means of the pendent arms l l, and clinkers and grit are easily crushed between the bars during their vibratory motion.

Sometimes I propose to cast pins or spikes upon the upper edges of the bars k k, to facilitate the riddling operation, and to break up large clinkers in the body of the fire.

For packing between the feeder and the corrugated cap E, I generally use fire-clay.

Between the cap and the shell D, sand is employed in the channel a.

From the rear end of the corrugated cap E depends the smoke-pipe L, extending downward for a distance, and then bending upward, and communicating with the radiator at its rear end.

M designates a prismatic or cylindrical radiator, arranged in position over the furnace, and extending longitudinally through the upper part of the hot-air chamber P, within the brick walls B.

From the lower portion of the front end of the radiator projects the horizontal pipe r, provided with a cap, s. The exit-flue t, for the smoke, is joined to the upper side of this pipe. Somewhat higher up, on either side of the pipe r, project similar smaller pipes, v v, provided with caps, and serving for cleaning purposes. The large pipe r, at the base of the smoke-pipe t, is designed, also, to facilitate the cleaning of the radiating drum.

The walls of the drum are connected by the diagonal pipes R R, connected, alternately, by the short elbows u u, to the brick walls B B, on each side. By this arrangement, the cold air from without is carried immediately through the heated radiator. External air is also admitted at the base of the wall B, at a point, N, near the rear end of the chamber. This air is heated by the furnace proper, smoke-pipe, and the external wall of the radiator. The heated products of combustion pass into the radiator at a point, a', in its base, then rise, and pass forward along the top and downward, creating a current, which is broken con-

tinually by the diagonal pipes R R, and eventually finds exit at the point b'.

In the construction of my radiator, the pipes R R are joined to the wall thereof, at each end, by means of a double flanch, e', as shown at fig. 3.

The heads S' of the radiator are flanch'd, and sunk into the ends of the wall, the flanches being then bent over the edges of the wall, and the heads then secured in place by rivets.

The cylinder is usually made in two long sections, M' M', riveted together by means of horizontal flanches, w w, in the manner shown.

Sometimes, in heating small houses, I prefer to use the drum without connecting it to the walls B B. In such cases all the air is admitted at the point N, and passes not only around the radiator, but through the diagonal pipes R R.

What I claim as my invention, and desire to secure by Letters Patent, is—

1. The radiator M, provided with the cleaning-pipes v v r, and the internal diagonal flues R R, as specified.

2. In combination with the corrugated cap E, provided with flanch e and bead c, the feeding-pipe F and corrugated shell D, provided with flanch d, and channel a.

3. In combination with the tapering corrugated shell D, the lining-plate G, provided with the perforations n n, and the flues z z, leading to the air-chamber H, between the plate and shell.

In testimony that I claim the above, I have hereunto subscribed my name in the presence of two witnesses.

GEO. H. MILLER.
